Attorney

UNITED STATES PATENT OFFICE.

WILLIAM W. WILSON, OF DALLAS, TEXAS.

CHURN.

1,333,360.

Specification of Letters Patent.

Patented Mar. 9, 1920.

Application filed November 18, 1919. Serial No. 338,885.

To all whom it may concern:

Be it known that I, WILLIAM W. WILSON, a citizen of the United States, residing at 429 Page avenue, Station A, Dallas, in the 5 county of Dallas and State of Texas, have invented certain new and useful Improvements in Churns, of which the following is a specification, reference being had therein to the accompanying drawing.

10 This invention relates to certain new and useful improvements in churns and more particularly to an improvement on a construction of churn disclosed in Patent No. 1,268,766, L. M. Payne, R. A. Thompson and L. P. Morris, June 4, 1918, the object 15 being to provide a construction of cover which is exceedingly simple and cheap and one which is so constructed that the contents of the receptacle will be prevented from slushing out when the churn is agitated.

Another and further object of the invention is to provide novel means for supporting the dasher within the body of the churn in order to allow the same to be readily 25 inserted or removed for cleaning.

Other and further objects and advantages of the invention will be hereinafter set forth and the novel features thereof defined by the appended claims.

30 In the drawings:

Figure 1 is a vertical section of my improved construction of churn in elevation.

Fig. 2 is a perspective view of a dasher detached.

35 Fig. 3 is a detailed section of a slightly modified form of a cover; and

Fig. 4 is a similar view of still another modified form.

In carrying out my invention I employ 40 a base 1 provided with apertures 2 at each end through which is adapted to extend the vertical arms 3 of a substantially U-shaped clamping member 4. The upper ends of the arms 3 are threaded as shown at 5 and 45 are adapted to extend through apertures formed in the clamping bar 6 and are provided with wing nuts 7 for the purpose hereinafter fully described.

Mounted on the base 1 is a receptacle 8 50 having a reduced neck portion 9 provided with an annular bead 10. A cover 11 of substantially inverted cup-shape is placed over the neck and is clamped tightly in position thereon by the clamping bar 6 as 55 clearly shown in Fig. 1.

The churn is supported between springs 12 and 13, spring 13 being carried by a bracket 14 and having its lower end connected to an eye carried by the clamping bar 6. The spring 12 has its lower end 60 connected to the base and its upper end to an eye carried by the base 1 whereby the churn is agitated in substantially the same manner as that shown in the above referred to patent. The body of the receptacle is 65 formed with an annular bead 15 within the receptacle adapted to receive the looped wire ends 16 of a bar 17 whereby the flexibility of the wires allow the dasher to be inserted or removed. In constructing the dasher as 70 shown a strip of metal is employed over which is arranged an oval shaped ring of wire and the edges of the metal are turned around the parallel bars of the ring of wire as shown in Fig. 2 so as to secure the same 75 thereon. This forms the body of the dasher and a cross bar 18 is secured to the body and is preferably arranged diagonally as shown, the cross bar and body being formed with apertures for agitating the contents of the 80 receptacle.

In the construction shown in Fig. 3 the neck 19 of the receptacle is provided with a cover 20 and an opening constructed substantially in the same manner as paint cans 85 now in use.

In Fig. 4 the receptacle is provided with a plug cover 22.

When the churn constructed with a cover as shown is placed upon the support 1 and 90 the clamping bar 6 is in position upon the arms of the U-shaped member by tightening the thumb nuts the cover will be forced downwardly in position so as to form a liquid tight joint. By constructing the 95 dasher in the manner shown the same can be readily inserted or removed and is supported rigidly when in position.

From the foregoing description it will be seen that I have provided a churn with 100 a cover so constructed that a liquid tight joint is formed without the use of a gasket of any kind.

What I claim is;—

1. A churn comprising a receptacle having oppositely disposed seats and a dasher having flexible ends adapted to be sprung within said seats. 105

2. A churn comprising a removably supported receptacle having an annular inte- 110

rior groove, a dasher formed of a pair of members arranged at an acute angle to one another, one of said members being provided with wire loops at its end adapted to be seated within the groove of said receptacle.

3. A churn comprising a removably supported receptacle having an annular interior groove and a dasher having flexible

ends adapted to be sprung within said 10 groove.

In testimony whereof I have hereunto affixed my signature in the presence of two witnesses.

WILLIAM W. WILSON.
